APPARATUS FOR MIXING AND FILLING
BEVERAGES

Robert J. Stewart, Baltimore, Md., assignor to
Crown Cork & Seal Company, Inc., Baltimore,
Md., a corporation of New York

Application February 14, 1940, Serial No. 318,964

8 Claims. (Cl. 259—8)

1

The present invention relates to apparatus for mixing and filling beverages.

In the production of beverages such as soft drinks, consisting of carbonated water and syrup, it has been usual to separately flow syrup and carbonated water into a bottle or other container and then bodily move the container in some manner, either by hand or by machine, to cause the two liquids to be properly mixed. Such subsequent bodily movement of the container has been necessary to obtain mixing because of the fact that the body of heavier syrup tends to remain at the bottom of the bottle.

In order to avoid the necessity of the mixing step discussed above, as well as the labor and apparatus required thereby, various methods of mixing the two liquids prior to the flowing of the same into a bottle have been proposed.

It has been found that by mixing the syrup and water prior to flowing into a container, the filling can be accomplished more quietly since the possibilities of foaming during filling are reduced and a more uniform proportion of syrup and water is obtained.

By one such process, syrup and plain water have been mixed and then carbonated together. Such an arrangement causes the syrup to come into contact with the interior of the carbonator as well as a substantial extent of the piping included in the mixing apparatus. Bottling concerns ordinarily handle several soft drinks, each including a different syrup. Obviously, it is desirable to keep the amount of surface or piping with which the syrup comes in contact at a minimum, since all such surface must be washed or flushed before the apparatus can be used to handle a different soft drink.

Another objection to prior methods for mixing carbonated beverages is that they have too greatly agitated the mixture. One particular cause of agitation has been the manner in which the ratios of the two liquids have been maintained.

An important object of the present invention is to provide an improved method of filling liquids.

Another important object of the present invention is to provide a method and apparatus whereby liquids may be mixed and filled without undue agitation thereof.

Another object of the invention is to provide a method and apparatus for mixing liquids which are so designed that the proper ratios of the liquids comprising the mixture will be accurately maintained.

Still another object of the invention is the

5

provision of a method and apparatus of the type referred to above which is readily adapted to handle various mixtures without the necessity of flushing a large number of the elements of the apparatus.

10

A further object of the invention is the provision of an apparatus and method for mixing liquids under varying pressures while maintaining the proper proportion of each liquid.

15

Other objects and advantages of the invention will be apparent from the following specification and drawings, wherein:

Figure 1 is a diagrammatic view of the apparatus of the present invention.

Figure 2 is a view diagrammatically showing the wiring system used in the apparatus of Figure 1.

Figure 3 is a detail section on the line 3—3 of Figure 1.

Figure 4 is a vertical sectional view through a mixing device included in the present invention.

Figure 5 is a horizontal sectional view on the line 5—5 of Figure 4.

Figure 6 is a vertical sectional view through a settling tank included in the invention.

Figure 7 is a top view of a gas trap included in the present invention.

Figure 8 is a side elevation, partly in section, of the gas trap of Figure 7, and

Figure 9 is a side elevation of a second form of gas trap.

20

Referring to Figure 1, the numeral 10 designates a carbonator for carbonating water delivered thereto through the line 11 from a pump 12 operated by a motor 13. The carbonator 10 is of any well-known form including a liquid level control for the motor 13, and the water carbonated thereby will flow from the same through the pipe 14 to a gas trap 15, hereinafter described in detail, and thence to a water pump 16.

25

Water pump 16 is driven by a shaft 17 driven through a belt 18 by a variable speed transmission device 19, hereinafter fully described.

30

The speed transmission device 19 is driven through a belt 20 from the shaft 21 of gear reduction unit 22 which is in turn driven through a belt 23 by a motor 24.

35

The driven shaft 21 of the gear reduction unit 22 extends to a pump 26 to which the syrup supply line 27 is connected through a gas trap 28.

40

Water flows from the water pump 16 through a line 30 to a water meter 31 and syrup flows from the syrup pump 26 through a line 32 to a syrup meter 33. The two meters 31 and 33 may be of any well-known type, for example of the

2

provision of a method and apparatus of the type referred to above which is readily adapted to handle various mixtures without the necessity of flushing a large number of the elements of the apparatus.

A further object of the invention is the provision of an apparatus and method for mixing liquids under varying pressures while maintaining the proper proportion of each liquid.

Other objects and advantages of the invention will be apparent from the following specification and drawings, wherein:

Figure 1 is a diagrammatic view of the apparatus of the present invention.

Figure 2 is a view diagrammatically showing the wiring system used in the apparatus of Figure 1.

Figure 3 is a detail section on the line 3—3 of Figure 1.

Figure 4 is a vertical sectional view through a mixing device included in the present invention.

Figure 5 is a horizontal sectional view on the line 5—5 of Figure 4.

Figure 6 is a vertical sectional view through a settling tank included in the invention.

Figure 7 is a top view of a gas trap included in the present invention.

Figure 8 is a side elevation, partly in section, of the gas trap of Figure 7, and

Figure 9 is a side elevation of a second form of gas trap.

Referring to Figure 1, the numeral 10 designates a carbonator for carbonating water delivered thereto through the line 11 from a pump 12 operated by a motor 13. The carbonator 10 is of any well-known form including a liquid level control for the motor 13, and the water carbonated thereby will flow from the same through the pipe 14 to a gas trap 15, hereinafter described in detail, and thence to a water pump 16.

Water pump 16 is driven by a shaft 17 driven through a belt 18 by a variable speed transmission device 19, hereinafter fully described.

The speed transmission device 19 is driven through a belt 20 from the shaft 21 of gear reduction unit 22 which is in turn driven through a belt 23 by a motor 24.

The driven shaft 21 of the gear reduction unit 22 extends to a pump 26 to which the syrup supply line 27 is connected through a gas trap 28.

Water flows from the water pump 16 through a line 30 to a water meter 31 and syrup flows from the syrup pump 26 through a line 32 to a syrup meter 33. The two meters 31 and 33 may be of any well-known type, for example of the

construction disclosed in Hosmer Blum Patents Nos. 1,423,597, issued July 25, 1922, and 1,977,424, issued October 16, 1934. However, each meter should be of such type that it will accurately measure a liquid, regardless of changes in the delivery pressure of the liquid.

The shafts 34 and 35 of meters 31 and 33 which are driven by the meters to register or indicate the flow of liquid therethrough are extended from the respective meters and, as shown in detail in Figure 3, the shaft 34 of one of the meters, in the present instance, the water meter 31, carries a slip clutch 36 through which it is connected to a splined shaft 37. The shaft 35 of the other meter carries a slip clutch 38 through which it drives a threaded shaft 39 which extends co-axially with the shaft 37, the adjacent ends of shafts 37 and 39 being substantially in abutting relation. A collar or traveling nut 40 bridges the two abutting shafts, the end portion of nut 40 which engages splined shaft 37 being keyed and the other end portion of the nut being threaded to engage shaft 39.

Collar 40 is engaged by a yoke 41 carried by a lever 42 extending to the speed change device 19 and pivoted intermediate its ends as indicated at 43. At its far end the lever 42 engages the operating handle 44 of the speed change device. By this arrangement, if one of shafts 37 and 39 is driven by a meter to rotate at a different speed from the other, the traveling unit 40 will move in a direction further along the faster rotating shaft, thereby shifting lever 42 with a resulting actuation of the operating handle 44 of speed change device 19. During such movement the clutches 36 and 38 will not slip, but only upon extreme movement of the nut as hereinafter described.

The speed change device 19 may be of any well known type whereby gradual changes of speed can be obtained. However, in the present embodiment it is of a type including a driving and a driven pulley connected by a belt; one pulley comprising facing convex discs urged together on their common shaft by a coil spring. When the distance of either pulley axis from the other is varied, the belt connecting the two pulleys will be caused to engage a different diameter of the tapered faces of the multidisc pulley with the result that a change in speed of the driven pulley will be obtained.

It will be obvious from the above that the speed change device 19 will thus control the speed of operation of the water pump 16 so as to hold the supply of water flowing from the water meter 31 at the proper proportion with respect to the supply of syrup leaving the syrup meter 33. In most soft drinks, one part of syrup is mixed with five parts of water, but the arrangement provided herein may be varied to maintain whatever ratio is desired.

The outlet of the water meter 31 is connected by a pipe 45 to the inlet 46 of the mixing device 47 and the outlet of the syrup meter 33 is connected by a line 48 to a second inlet 49 of the mixing device.

Referring to Figure 4, which illustrates the mixing device 47 in detail, it will be noted that the water inlet 46 is of relatively large diameter and, as best shown in Figure 5, is arranged eccentrically with respect to a vertical tube portion 50 of the inlet, with the result that the water will have a swirling motion as it moves down through tube portion 50. The syrup line 48, of smaller bore than water line 45, is connected to

a tube 51 of small bore which extends downwardly through the center of tube 50. Thus the water and the syrup will enter the mixing device 47 from the same direction and in generally concentric streams. The fitting or tube 50 is formed in the top wall 53 of a cylindrical chamber 54, the body of which is preferably of glass. A rotating cylindrical element 55 of substantially less length than the chamber 54 is fixed upon a shaft 56 extending down through the lower wall of the chamber. Element 55 is of such diameter that a relatively small space will be left between its periphery and the inner surface of chamber 54 and the outer surfaces of the cylinder are smooth so as to minimize agitation. Externally of the chamber 54 shaft 56 is provided with a pulley 57 driven through a belt 58 by a motor 59.

The lower wall 60 of chamber 54 includes an extension 61 surrounding the shaft 56 and through which the mixed liquid will flow to a line 62 extending to a settling tank 63.

The rotary element 55 within the mixing device cylinder 54 is rotated at a relatively high speed in order that the incoming syrup and water will be thoroughly mixed. However, since the element 55 is perfectly smooth, its rotation will not cause release of gas in the carbonated water being mixed. That is, the syrup and water entering the chamber 54 in a generally concentric stream will move down upon the upper surface of the drum 55 rotating in the same direction as the liquids are swirling. However, since the drum 55 is rotating at a more rapid speed it will cause the relatively thin body of liquid between its upper surface and the undersurface of the top wall 53 of the chamber to swirl with a faster motion so that the two liquids will be further intermingled. Then, when the liquids move down between the relatively narrow space between the side surface of the rotating drum 55 and the inner wall of the chamber 58, they will be completely mixed due to the opposing frictional action exerted by the stationary chamber wall and that of the rotating drum.

It is desirable to provide a check valve 64 in the syrup inlet tube 51 so that should the supply of syrup fail for any reason, water will not enter the syrup line 48. Check valve 64 is so mounted and controlled that it will not interfere with the flow of syrup under pressure past the same.

The settling chamber 63 is illustrated in detail in Figure 6 and is of cylindrical form, the syrup and water line 62 opening to the lower wall 67 of the device to a pipe 68 which extends a substantial distance up into the chamber. A float 69 is pivoted in the chamber 63 in such position that the level of the liquid within the settling chamber will normally be above the inlet extension 68 but will also be a substantial distance below the upper end of the cylinder.

Chamber 63 is provided with an outlet 70 in its lower wall 67 from which a line 71 extends to the reservoir 72 of the filling machine 73. The float 69 is connected exteriorly of the settling chamber 63 with a switch, preferably a mercury type switch, within a casing 75, the purpose of switch 75 being to control the main driving motor 24 so that should the level of the liquid in chamber 63 rise to an extreme extent, the motor 24 will be stopped. The float rod is also connected within casing 75 to a valve mechanism, not shown, connected to a pressure fluid line 76 to control flow through lines 76a and 76b to a pressure cylinder 77 adjacent motor 24 as shown in

Figure 1. A piston rod 78 extending from cylinder 71 is secured to motor 24 and the motor is mounted upon slideway 79.

The operation of the valve mechanism in casing 75 is such that if the level of the liquid in chamber 63 drops, the valve mechanism will be actuated to cause pressure flow through line 76a so that this pressure will act upon one side of the piston in cylinder 71 to draw motor 24 closer to the cylinder 71 and also closer to the gear reduction unit 22. Motor pulley 24a includes two tapered discs as described above in connection with the speed-change device 19 and a decrease in the distance between motor 24 and the gear reduction unit 22 will therefore cause unit 22 to be driven at a higher speed so as to increase the speed of the pumps 16 and 26 to supply more liquid to settling chamber 63.

If the float 69 in the settling chamber is raised slightly by the liquid level, the valve mechanism controlled thereby will cause pressure to act through line 76b upon the opposite side of the piston in cylinder 71, thereby moving piston rod 78 to slide the motor 24 away from unit 22 so that the speed of the pumps 16 and 26 will be decreased. As stated above, if the float 69 rises too far, the circuit to the motor 24 will be closed until the float again drops somewhat.

The provision of the settling chamber 63 enables the liquid to move to the reservoir 72 of the filling machine in a quieter condition than would be the case if the reservoir received the liquid direct from the mixing device 46.

In order that the fluid in filling machine reservoir 72, settling tank 63 and carbonator 10 will be under the same pressure, the top portions of these three elements are connected by pressure equalizing lines 80 as indicated in Figure 1. This will prevent a pressure lock at any point in the system.

Settling chamber 63 is of such capacity that liquid will be held in the same for approximately ten minutes. That is, in normal operation, the chamber will be filled, and the pumps 16 and 26 will then stop until the level in chamber 63 falls. During this settling period any fine bubbles in the mixture will either rise out of the mixture or will go into solution. This action will be aided by reason of the fact that the pressure in chamber 63 is the same as in the carbonator 10, by reason of the connecting lines 80. Also, the settling chamber is insulated to maintain the mixture at the proper cool temperature. It is desirable to provide such insulation at other parts of the apparatus as is necessary to maintain the liquids at proper temperature throughout travel through the various elements of the system.

The gas trap 28 illustrated in Figure 1 as associated with the syrup pump 26 is shown in detail in Figures 7 and 8 and comprises a lower chamber 85 and an upper chamber 86. The syrup inlet line 27 enters the upper portion of the chamber 85 at a point offset with respect to the axis of the chamber so that the syrup will have a swirling motion as it moves downwardly through that chamber to the line 87 which extends to the inlet of pump 26. The swirling motion of the liquid will allow any entrained gases to collect at the center and rise through the short tube 88 extending from the central portion of the top of chamber 85 to the upper chamber 86. Chamber 86 has a float 89 therein including an arm 90 fixed to a rod 91 journaled in the chamber. Arm 90 carries a valve 92 normally adapted to close an escape port 93. If gas or air enters

the lower chamber 85 to such an extent that the level of the liquid normally in upper chamber 86 drops, float 89 will drop to open the valve 92 so as to permit the escape of gas through port 93. Should the float 89 drop to a marked extent, a switch in a casing 95 adjacent the upper chamber 86 will be operated by rod 91 to an opened position to open the circuit to the motor 24, thereby stopping the entire apparatus.

10 The gas trap 15 provided upon the water pump 16 is illustrated in Figure 9 and includes a lower chamber 85a and an upper chamber 86a. Carbonated water enters the lower chamber 85a from line 14 through an inlet port 96 which is offset with respect to the axis of the lower chamber so that the incoming water will be given a swirling motion. In order that the swirling motion will be continued throughout the movement of the water through the chamber, the outlet line 97 which conducts the carbonated water to the water pump 16 is also offset with respect to the axis of chamber 85. The gas trap 15 is otherwise identical to the syrup gas trap 28.

Figure 2 diagrammatically illustrates the manner in which the various elements of the apparatus are electrically connected so that the motor 24 which operates the water pump 16 and syrup pump 26 will be stopped in the event that the apparatus is producing too great a quantity of mixed beverage, or if the supply of water or syrup fails. Referring to Figure 2, it will be noted that a main 120 is connected to one connection of the motor 24 while another main 121 is connected to the float operated control switch within the casing 75 of the settling chamber 63. From this latter switch a series lead 122 extends to the float control switch associated with the gas trap 15 of the water pump and a series lead 123 extends from this switch to the switch associated with the gas trap 28 of the syrup pump. A lead 124 connects the last-mentioned switch with a normally closed trip switch 125 arranged at one side of the path of movement of the lever 42. A second normally closed trip switch 126 is positioned at the other side of the path of movement of lever 42. The provision of these two trip switches insures that if the speed of movement of either of the meters 31 and 33 either drops or increases to a marked extent, the motor 24 will be stopped by reason of the fact that the lever 42 will actuate one of the two trip switches to opened position. The slip clutches 36 and 38 illustrated in Figure 3 insure that the shafts 37 and 39 which carry the traveling nut 40 will slip with respect to the meter shafts 34 and 35 when the lever 42 contacts with a trip switch and further swinging movement of the lever is prevented. This arrangement will prevent damage to the meters.

The two trip switches are connected in series by a lead 127 and a series lead 128 extends from trip switch 126 to the motor 59 which operates the mixing device. From motor 59 a lead 129 extends to the other side of the motor 24.

It will be observed from the above wiring diagram that motor 24 will be stopped if any of the switches in series circuit therewith is opened and that the mixing device motor 59 will be stopped at the same time.

It will be observed that the various controls and speed-change arrangements included in the present apparatus will insure that so long as the apparatus is operating, a mixture of the proper proportions of the constituent liquids will be produced and that if conditions become such that the apparatus cannot produce the proper mix-

ture, operation will immediately terminate. This is, of course, highly important in the production of soft drinks because the failure to maintain the exactly proper ratios will not be apparent from a mere viewing of the bottled product and it is not practicable to test the mixture from time to time. Therefore, unless a mixing apparatus is fully controlled as described above, a large number of bottles might be filled with a mixture of improperly proportioned constituent liquids, involving a substantial waste in both ingredients and labor.

The operation of the apparatus and method is as follows:

The water flowed to the carbonator 10 is preferably filtered and de-aerated in accordance with the usual practice and is cooled to a temperature just above freezing. The syrup flowed to the apparatus throughout line 27 is also cooled to the proper temperature to cause it to properly mix and so that it will not raise the water temperature too markedly. After carbonation the water flows to the gas trap 15 and is then forced by the pump 16 to the meter 31. The incoming syrup moves through the gas trap 28 and is then delivered by the pump 26 to the syrup meter 33. The meters 31 and 33 will deliver the proper proportions of syrup and water, usually at the rate of one ounce of syrup to five ounces of water, to the mixing device 47 where the two ingredients will be thoroughly mixed without agitation and will then flow through the line 62 to the settling chamber 63 from which the mixture will move through line 71 to the usual reservoir 72 of the filling chamber.

Since the entire system will be kept at the water carbonating pressure, the mixture in the settling tank and in the filling machine reservoir will be under an excessive gas pressure so as to increase its stability and permit filling at a greater range of temperatures. This renders the system applicable to numerous types of filling machines.

The provision of the settling chamber 63 at a point in advance of the filling machine reservoir 72 will permit the fine bubbles which may possibly be formed in the metering and mixing operations to pass either into solution or out of the liquid, insuring that the liquid can subsequently be quietly flowed into the bottles by the filling machine.

The inclusion in the system of a positively acting mixing device will insure that the syrup will be uniformly dispersed throughout the carbonated water. However, it will be noted, as stated in detail above, that the mixing device 47 disclosed herein is of such type that the mixture will not be unduly agitated. The method included in the present invention of controlling the mixture by changing relative pump speed also contributes to smoother operation and decreases churning and agitation of the liquids moving through the system.

Although the present method and apparatus have been generally described as adapted to handle the mixing of carbonated water and syrup, it will be appreciated that the invention is applicable to the mixing of numerous other liquids, particularly those which must be mixed under pressure or which contain gas in solution.

The terminology used in the specification is for the purpose of description and not of limitation, the scope of the invention being set forth in the claims.

I claim:

1. A device for mixing liquids comprising a chamber provided with a cylindrical bore including an uninterrupted cylindrical surface, inlets for liquid adjacent one end of the chamber, an outlet for liquid adjacent the opposite end of the chamber, a cylinder including a smooth periphery rotatable in the chamber, means to rotate the cylinder, the cylinder being of less length than the chamber and positioned closely adjacent the inlet end thereof and being of such diameter with respect to the inner diameter of the chamber as to provide an area of limited radius between the cylinder and chamber walls in which liquids may be swirled together to mix, the radius of the area being so limited as to preclude foaming.
2. A device for mixing liquids comprising a cylindrical chamber, a cylinder rotatable in the chamber and spaced from each end thereof, means to rotate the cylinder, and inlets for the liquids to be mixed at one end of the chamber, at least one of the inlets being arranged to deliver liquid to the chamber at a point offset with respect to the axis of the rotatable cylinder.
3. A device for mixing liquids comprising a cylindrical chamber, a cylinder rotatable in the chamber and spaced from each end thereof, the cylinder being provided with a smooth periphery, means to rotate the cylinder, and inlets for liquids at one end of the chamber, at least one of the inlets being arranged to deliver liquid to the chamber at a point offset with respect to the axis of the rotatable cylinder.
4. In an apparatus for mixing liquids, a plurality of sources of liquids to be mixed, a liquid mixing means, a plurality of liquid flow lines, each flow line extending between one of said sources and said liquid mixing means, means in each line to move a liquid therethrough, a measuring means in each line, and means controlled by said measuring means to hold all of said liquid moving means at such relative speeds as to maintain a predetermined ratio of flow from said measuring means.
5. In an apparatus for mixing liquids, a plurality of sources of liquids to be mixed, a liquid mixing means, a plurality of liquid flow lines, each flow line extending between one of said sources and said liquid mixing means, means in each line to move a liquid therethrough, a measuring means in each line, means controlled by said measuring means to hold all of said liquid moving means at such relative speeds as to maintain a predetermined ratio of flow from said measuring means, a settling tank to receive the mixed liquid from said mixing means, and means associated with said settling tank to control the operation of said liquid moving means.
6. In a liquid mixing apparatus, a casing provided with a vertically extending cylindrical bore of uniform diameter, an inlet tube for one liquid arranged concentric with the axis of the casing bore and opening to the upper end of the casing bore, a second inlet tube for a second liquid surrounding and arranged concentrically with respect to the first-mentioned tube, means to flow liquid tangentially into said second tube whereby the second liquid will move into and downwardly in said second tube and thence into the casing bore with a swirling motion, a rotary drum mounted concentrically in the bore of said casing, said drum being of such diameter that only a small space will be provided between the drum periphery and the casing bore, the upper end of said drum being positioned adjacent said concentric

tric inlets so that the incoming liquids will move down upon the top of the drum, and means to rotate said drum with a movement faster than the swirling motion of the liquid entering through said second tube so that the liquids will be thoroughly intermingled during movement downwardly between said drum and casing bore.

7. A liquid mixing apparatus of the character described in claim 6 wherein the rotary drum is of substantially less length than the casing bore 10 and has its lower end spaced a substantial distance from the lower end of the casing bore.

8. In an apparatus for mixing liquids, a plurality of sources of liquids to be mixed, a liquid

mixing means, a plurality of liquid flow lines, each flow line extending between one of said sources and said liquid mixing means, means in each line to move a liquid therethrough, a measuring means in each line, means controlled by said measuring means to hold all of said liquid moving means at such relative speeds as to maintain a predetermined ratio of flow from said measuring means, a settling tank to receive the mixed liquid from said mixing means, and means associated with said settling tank to control the speed of operation of said liquid moving means.

ROBERT J. STEWART.
